UNITED STATES PATENT OFFICE.

EUGENE H. LEDERER, OF STATE COLLEGE, PENNSYLVANIA.

VEGETABLE SLICER.

Application filed December 20, 1924. Serial No. 757,207.

To all whom it may concern:

Be it known that I, EUGENE H. LEDERER, a citizen of the United States, residing at State College, in the county of Center and State of Pennsylvania, have invented certain new and useful Improvements in Vegetable Slicers, of which the following is a specification.

This invention relates to a vegetable slicer, designed primarily for the slicing of potatoes, but it is to be understood that a machine in accordance with this invention is adapted for use for slicing any class of vegetables or fruits for which it is found applicable, and the invention has for its object to provide, in a manner as hereinafter set forth, a machine of the class referred to with means for expeditiously and uniformly slicing the article acted upon in lattice-like corrugated or other forms.

Further objects of the invention are to provide, in a manner as hereinafter set forth, a slicing machine which is comparatively simple in its construction and arrangement, strong, durable, compact, thoroughly efficient in its use, readily assembled, conveniently operated, and comparatively inexpensive to set up.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is an elevation of a slicing machine in accordance with this invention.

Figure 2 is a top plan view thereof.

Figure 3 is a section on line 3—3, Figure 2.

Figure 4 is a section on line 4—4, Figure 2.

Figure 5 is a top plan view of a set of claims.

Figure 6 is a fragmentary view in section illustrating a knife edge.

As illustrated, the machine is mounted upon and secured to a concrete base 1, and the machine includes a hollow supporting

standard 2 provided at its bottom with apertured lugs 3, through which extend hold-fast devices 4 embedded or anchored in the base 1, whereby the standard 2 is fixedly secured in position. The standard 2 is of tapered contour and gradually decreases in diameter from its lower towards its upper end, and intermediate the ends thereof is provided with a series of spaced laterally extending integral supporting members 5, upon which is adapted to be mounted a receptacle or receptacles for receiving the slices of the vegetable or fruit. The upper end of the standard 2, at a point removed from its top edge, is formed with an interiorly arranged annular shoulder 6 and below the shoulder with a cylindrical opening 7, having integral with the wall thereof a lengthwise extending rib 8 which constitutes a key.

Extending into the opening 7, and projecting a substantial distance above the standard 2, is a vertically disposed shaft 9, provided at a point between its transverse center and its lower end with an integral collar 10 seating on the shoulder 6. That portion of the shaft 9 below the collar is provided with a key-way or groove into which extends the rib or key 8, whereby the shaft 9 is prevented from shifting relative to the standard 2. That portion of the shaft 9, above the collar 10, is of greater length than that portion arranged below the collar 9; and the said upper portion of the shaft 9 is indicated at 11, and said part 11 has reduced upper portions 12 and 13, the latter being of less diameter than the former, and the said reduced portion 12 forms the part 11 with a peripheral shoulder 14. The reduced portion 13 is peripherally threaded.

Surrounding the part 11, of the shaft 9, is a bearing sleeve 15 which abuts against a bearing disk 16 seated on the collar 10. Mounted on the sleeve 15 is the hub 17 of a revolvable knife carrier 18. The hub 17 is positioned against and fixedly secured, by hold-fast devices 19, to the disk 16, whereby the latter will be bodily carried with the hub 17 during the operation of the knife carrier 18.

The knife carrier 18 not only includes the hub 17 and disk 16, but furthermore includes a series of spokes 20, which are integral with the lower portion of the hub 17 and terminate in the inner rim 21 of a knife support and which comprises the outer rim 116

21, an outer rim 22, and a web 23. The rim 21, as well as the rim 22, is in the form of a ring standing on edge, and the web 23 consists of a flat sectional annulus and with the sections thereof spaced from each other to provide discharge passages 24 for the slices. The web 23 is integral with the opposed faces of the rims 21, 22, and the upper face of the web 23 is positioned a substantial distance below the top edges of said rims.

10 The knife carrier 18 further includes a cam support 25 in the form of a flat annulus and which is integral with the outer side of the rim 22. The perimeter of the 15 lower face of the cam support 25 is beveled and toothed to provide a circular rack 26 which is engaged by a beveled gear 27, for the purpose of revolving the knife carrier. The gearing 27 is carried by a shaft 28 operated from a suitable means not shown.

25 The knife carrier is illustrated as provided with four knives or cutters arranged in circular form, but it is to be understood that the number of knives or cutters will correspond to the number of the vegetable hoppers to be hereinafter referred to. Each of the knives or cutters is concentric in form and consists of a shank 29, provided 30 at one end with an upstanding portion 30 formed with a fluted cutting edge 31. That end of the knife or cutter, formed with the fluted cutting edge 31, is beveled throughout as indicated at 32, and spaced 35 from the non-cutting end 33 of the adjacent shank 29, see Figure 3, and the spacing of the knives or cutters in the manner as stated, forms a passage 34 for the slices, and the passages 34 register with the openings 24. The knives or cutters are mounted on the upper face of the web 23, and are secured in spaced relation, by the hold-fast devices 35 which engage with the web 23.

40 Secured to the upper face of the support 25 is two pair of high cams and two pair of low cams, and said cams are employed for intermittently revolving the vegetable hoppers during the operation of the knife 45 carrier. The high cams are alternately disposed with respect to the low cams on the support 25. As the high cams are constructed similar to the low cams, the description of a pair of high cams will apply to a pair of low cams. One cam of each pair of high cams, as well as one cam of each pair of low cams, consists of a narrow block 36, having its inner edge extending at opposite inclinations from the center thereof as indicated at 37, 38, and one end of the block 36 is tapered as at 39. The other cam of each pair of high cams, as well as the other cam of each pair of low cams, consists of a narrow block 40 having its inner edge extending at opposite in-

5 70 elinations from the center thereof, as at 41, 42, and one end of the block 41 is tapered as at 43. When the cams of each pair are set up, they are arranged in spaced relation and with their inclined edges exposing each other. Each of the cams is concentric in contour and provided with openings for the passage of hold-fast devices to fixedly secure the cams into position.

75 As shown, two pair of high cams are employed, and two pair of low cams, and the low cams are alternately disposed with respect to the high cams. Each pair of cams consists of an outer and an inner cam, but 80 the outer cams of each pair of high cams is of materially greater height than the inner cam of each pair of high cams. The height of the low cams are the same.

85 With reference to Figure 4, the outer cam of the pair of high cams is indicated at 44, and secured to the top thereof, by the hold-fast devices 44, 45, is an inwardly extending plate 46, having secured to the lower face thereof, by the hold-fast devices 47, the inner cam 48 of the pair of high cams.

90 With reference to Figure 2, the outer cam of a low pair of cams is indicated at 48, and which is secured, by the hold-fast devices 49, to a plate 50 mounted on the support 25, and the inner cam of the pair of low cams is indicated at 51, and which is secured to the plate 50 by the hold-fast devices 52. The hold-fast devices 49 and 52 100 fixedly secure the plate 50 in position. The cams 48 and 51 are arranged in spaced relation.

95 Keyed, as at 53, to the portion 12, of the shaft 9, is a collar 54, maintained against the part 11, of the shaft 9, by a clamping nut 55 engaging with the part 13 of the shaft 9. A washer 56 is interposed between the nut 55 and the collar 54. Formed integral with the collar 54 is a series of radially extending suspension arms 57, and each of which terminates at its outer end in a cylindrical holder 58, having the upper portion of its inner face flaring as at 59, and further provided with a shoulder 60 110 at the lower terminus of said flaring portion 59, and also with a lower portion 61 of the same diameter throughout and of greater diameter than the lower terminus of the flaring portion 59.

115 As illustrated, the collar 54 is provided with four suspension arms 57, and each of which is adapted to support a vegetable hopper, formed of a stationary upper section and a revolvable lower section. It is 120 obvious that the number of hoppers can be increased or diminished, but as before stated, the number of knives or cutters will correspond to the number of hoppers.

125 Each of said hoppers consists of a sta-

tionary upper section 62 and a revolvable lower section 63. The section 62 has a contracted lower portion 63, of tapering contour, which snugly fits the portion 59 of the holder 58, and said lower portion 63 of the section 62 is fixedly secured by the hold-fast devices 64 to the holder 58. The lower section 63 is cylindrical throughout, and has its inner face forming a continuation of the inner face of the section 62. Secured to the outer face of the section 63, at the upper portion thereof, through the medium of a series of rivets 65, is a bearing sleeve 66. Secured to the lower edge of the holder 58 is a flat ring 67, having its body portion of a width to extend from the outer face of the holder 58 to the outer face of the section 63. The ring 67 is secured to the holder 58 by the hold-fast devices 68 and acts not only as a support for the sleeve 66; but also couples the section 63 to the section 62; so that said section 63 can be revolved relatively to the section 62. The height of the section 63 is such as to extend in close proximity to the top edges of the rims 21, 22, of the knife support.

Secured against the outer face of the section 63, at the lower portion thereof, by the rivets 69, is a collar 70 provided with a set 70 of radially extending high arms 71 and a set of radially extending low arms 72. The arms 71 are arranged above the arms 72, and each of said arms 71 carries an actuating roller 73, and each of the arms 72 carries an actuating roller 74. The rollers 73, which may be termed a "high" set of rollers, engage the high cams for the purpose of revolving the section 63 and the rollers 74, which may be termed a "low" set of 40 rollers, engage the low cams for the purpose of revolving the section 63.

By reference to Figure 2 of the drawings, the hoppers are indicated at A, B, C and D, and the construction and arrangement of the 45 section 63 with respect to the knife carrier is such that when a roller 73 of hopper A is engaged by a pair of high cams, section 63 of such hopper will be revolved and shift the article to be acted on by the knife or cutter, and after such action, roller 74 will be engaged by a low pair of cams, and which will also shift section 63 of hopper A. The sections 63 of the hoppers are alternately revolved by the high and low cams, and by 50 this arrangement, it is obvious that the slices will be of lattice-like form, due to the fact that the cutting edges of the knives or cutters are corrugated, and the article will be acted on so that the pair of cutters forming a slice will operate in opposite directions on and with respect to the article. The position of the knives or cutters do not change; but the position of the article or vegetable does, due to the fact that after a cut the section 63 is shifted a part of a revolution,

say from forty-five to ninety degrees, bodily carrying the article therewith.

Arranged within each of the sections 63 of the hoppers is an upper and a lower set of clamps for the article or vegetable, and 70 the lower set will retain the article or vegetable in position to be acted upon by a knife or cutter, and such article will be forced downwardly by the weight of the superposed articles or vegetables. With 75 reference to Figure 4, the upper set of clamps is indicated at 75 and the lower set of clamps at 76. Each of the clamps of the upper and lower sets consists of a spring controlled arm 77, hinged at its upper end to a keeper 78. The controlling springs for 80 each of the clamps is indicated at 79; and one end of the spring is anchored in the section 63 and the other end is secured to the lower portion of an arm, and the springs of each 85 set maintain the arms of each set in a position to extend toward each other at an inclination. The upper set of clamps extend in the upper portion of the lower set of clamps, and the lower set of clamps extend 90 at a point in proximity to the lower edge of the section 63. The article or vegetable to be operated on passes down between the sets of clamps and the article is forced from the upper set to the lower set by the weight 95 of the articles bearing thereon. The lower set of clamps, as before stated, maintains the article in a position to be acted upon by the knives or cutters during the revolving of the knife carrier.

The construction and arrangement of the machine will provide means whereby the slices, after the first slice, will be of lattice-like form, and the sets of clamps are so arranged within the lower sections of the hoppers to provide for the positioning of a single article or vegetable to be sliced, and it is obvious that after the article has been sliced, the slices will be discharged through the openings 24 into a suitable receptacle or receptacles carried by the supports 5. The hoppers are filled with, by way of example, potatoes, and the weight of the upper potatoes acting on the lower ones will provide for the successive feed of the potato towards the slicing mechanism. The springs 79 are of sufficient strength to maintain the clamp arms in the necessary position to provide for the proper feed of the potato. If desired, to insure the necessary feed, after a number of the potatoes have been sliced, the hoppers may have arranged therein followers of the desired weight to insure the feed. The arrangement of the cams with respect to the actuating rollers is to insure the shifting of the sections 63 intermittently, at predetermined times, after a slice from the article has been made by the cutter, and when the sections 63 are shifted, the potatoes within the sets of clamps are carried bodily there-

with. Although as before stated, the machine is illustrated with four hoppers and a corresponding number of cutters, yet it is to be understood that such number can be increased or diminished.

It is thought the many advantages of the slicing machine, for the purpose set forth, and in accordance with this invention, can be readily understood, although the preferred embodiment of the invention is as illustrated and described, yet it is to be understood that changes in the details of construction can be had which will fall within the scope of the invention as claimed.

15. What I claim is:

1. A slicing machine for the purpose set forth, comprising a revolvable carrier provided with a plurality of cutters, a plurality of article receiving hoppers suspended over said carrier and each including a stationary upper and a shiftable lower section, and coacting means mounted on said shiftable sections and said carrier for intermittently revolving said shiftable sections during the operation of the carrier to provide for the slicing of an article in lattice-like form.

2. A slicing machine for the purpose set forth, comprising a revolvable carrier provided with a plurality of cutters, a plurality of article receiving hoppers suspended over said carrier and each including a stationary upper and a shiftable lower section, coacting means mounted on said shiftable sections and said carrier for intermittently revolving said shiftable sections during the operation of the carrier to provide for the slicing of an article in lattice-like form, and means within each of said shiftable sections for releasably holding the article acted upon by the cutters.

3. A slicing machine for the purpose set forth, comprising a revolvable carrier provided with a plurality of cutters, a plurality of article receiving hoppers suspended over said carrier and each including a stationary upper and a shiftable lower section, coacting means mounted on said shiftable sections and said carrier for intermittently revolving said shiftable sections during the operation of the carrier to provide for the slicing of an article in lattice-like form, and said carrier provided with means for the discharge of the slices.

4. A slicing machine for the purpose set forth, comprising a revolvable carrier provided with a plurality of cutters and high and low cams positioned exteriorly of the cutters, a plurality of article receiving hoppers suspended over said carrier and each including a stationary and a shiftable lower section, and means carried by said shiftable sections and engageable with said cams for intermittently revolving said shiftable sections during the operation of the carrier.

5. A slicing machine for the purpose set forth, comprising a revolvable carrier pro-

vided with a plurality of cutters and high and low cams positioned exteriorly of the cutters, a plurality of article receiving hoppers suspended over said carrier and each including a stationary and a shiftable lower section, means carried by said shiftable sections and engageable with said cams for intermittently revolving said shiftable sections during the operation of the carrier, and means within said shiftable sections for releasably holding an article to be sliced by the cutters.

6. A slicing machine for the purpose set forth, comprising an intermittently revolvable article holder and including means for releasably holding an article to be sliced in the path of a cutter, a revolvable carrier arranged below said means and provided with a cutter acting on the article for slicing it, and coacting means carried by the holder and said carrier for intermittently revolving said holder during the operation of the carrier.

7. A slicing machine for the purpose set forth, comprising an intermittently revolvable article holder and including means for releasably holding an article to be sliced in the path of a cutter, a revolvable carrier arranged below said means and provided with a cutter acting on the article for slicing it, coacting means carried by the holder and said carrier for intermittently revolving said holder during the operation of the carrier, said carrier provided with discharge openings for the passage of the slices, and said openings arranged in proximity to said cutters.

8. A slicing machine for the purpose set forth, comprising a revolvable carrier provided with a plurality of cutters, a plurality of article receiving hoppers suspended over said carrier and each including a stationary upper section and a shiftable lower section swivelly connected to the lower portion of the upper section, and coacting means mounted on said shiftable sections and carrier for intermittently revolving said shiftable sections during the operation of the carrier.

9. A slicing machine for the purpose set forth, comprising a revolvable carrier provided with a plurality of cutters, a plurality of article receiving hoppers suspended over said carrier and each including a stationary upper section and a shiftable lower section swivelly connected to the lower portion of the upper section, coacting means mounted on said shiftable sections and carrier for intermittently revolving said shiftable sections during the operation of the carrier, and means within said shiftable sections for releasably holding an article to be sliced by the cutters.

10. A slicing machine for the purpose set forth, comprising a revolvable carrier pro-

vided with a plurality of cutters and high and low cams positioned exteriorly of the cutters, a plurality of article receiving hoppers suspended over said carrier and each including a stationary and a shiftable lower section, means carried by said shiftable sections and engageable with said cams for

intermittently revolving said shiftable sections during the operation of the carrier, and said carrier provided with means for 10 the discharge of the slices.

In testimony whereof, I affix my signature hereto.

EUGENE H. LEDERER.
